ELMER R. CORWIN, OF CHICAGO, ILLINOIS, ASSIGNOR TO CORWIN TELEPHONE MANUFACTURING COMPANY, OF CHICAGO, ILLINOIS, A CORPORATION OF ILLINOIS.

INTERCOMMUNICATING TRUNKING SYSTEM.

No. 918,660.

Specification of Letters Patent.

Patented April 20, 1909.

Application filed May 9, 1908. Serial No. 431,948.

To all whom it may concern:

Be it known that I, ELMER R. CORWIN, a citizen of the United States of America, residing at Chicago, in the county of Cook and State of Illinois, have invented a new and useful Intercommunicating Trunking System, of which the following is a specification, reference being had to the accompanying drawing, illustrating same.

10 My invention relates to intercommunicating telephone systems and deals in particular with trunking arrangements for such systems adapted to trunk with magneto exchanges.

15 The principal objects of my invention are to provide improved trunking arrangements for trunking between intercommunicating telephone systems and magneto exchanges; to provide improved means for signaling the magneto exchange from the various stations 20 of the intercommunicating telephone system; to provide improved talking circuits between common battery intercommunicating telephone systems and magneto telephone systems; to provide improved means for receiving 25 and handling incoming trunk calls from a magneto exchange, in such an intercommunicating telephone system; and to provide other improvements in a full-metallic common-battery intercommunicating telephone system having indicating ringing and listening keys, as hereinafter set forth.

30 Other objects will be apparent from the following specification.

35 My present invention provides a telephone system in which a number of stations are connected through impedances to a central source of talking current, each station being so arranged on the system that by means of suitable switching mechanism thereat it may 40 be connected with any of the other stations on the system as desired, for conversation between any two parties on the system, without the intervention of the ordinary telephone central switchboard, such connection 45 also permitting any of the other parties on the system to simultaneously converse with each other. At each station on the system is also provided switching mechanism associated with a central source of ringing current, whereby each of the parties on the system may ring any of the other stations as desired to signal same for conversation. In 50 addition to the above the system also provides switching mechanism and suitable apparatus whereby any of the parties on the

system may call out to a magneto central exchange over suitable trunk lines, one of the stations on the system (called the attendant's station) being provided with a signaling device on each of the trunk lines for receiving 60 incoming trunk calls from the magneto central exchange, and means whereby any of the other stations of the system may be called to respond to the incoming trunk calls.

65 The accompanying drawing illustrates diagrammatically a number of stations and trunk lines on the system of my present invention, in connection with suitable mechanism and connections for operating and utilizing the system.

70 The apparatus at the various stations 1, 2, 3, etc. is included between lines *f g*, *g i*, *i k*, etc. respectively.

75 Each of the stations on the system is provided with a plurality of push-button keys such as keys *T*, *T₂*, *H*, 1, 2, 3, etc., each key being provided with a pair of spring contact members 4 5 adapted to engage a pair of contact members 6 7, respectively, when the push-button 8 is depressed, and adapted to 80 lock in this depressed position so as to keep the said contacts closed. Each push-button switch or key, except the home keys *H* *H*, is also provided with a contact member 10 adapted to engage contact member 7 when 85 the push-button 8 is depressed past the locking position. All of the keys at any one station on the system are connected with a common locking mechanism whereby the depressions of any one of the push-buttons 8 90 releases any of the other keys at this station which may be in locking position, and allows same to return to normal position, each key being so constructed that it will return to its normal position when the locking mechanism is released. As there are known in the art several different locking keys and banks of keys which could be readily adapted for use in connection with this invention, it is not thought to be necessary to herein describe, in detail, any particular locking mechanism for the keys herein shown. In this connection it is believed to be sufficient to merely state that each of the keys shown in the drawing locks in a position in which 95 spring members 4 and 5 engage contacts 6 and 7, respectively, and that each key, except the home keys *H* *H*, is capable of being further depressed until contact 7 engages contact 10, not locking in this latter position 100 105 110

but returning to the aforesaid locking position when the pressure is removed from the button 8.

The local lines of the intercommunicating telephone system are designated on the drawing by *c*, *d* and *e*, respectively, the trunk lines being designated by *a* and *b*, respectively. Each of the keys at a station is adapted to connect the transmitter 19 and receiver 20 of that station across the corresponding local lines of the system, or across the corresponding trunk lines of the system, each home key *H* being adapted to connect the home transmitter 19 and receiver 20 across the home line.

Each of the telephones on the system is provided with a ringer 11 which is normally connected to one limb of its home line through suitable switch-hook contacts. The ringers 11 11 are all connected to one pole of the ringing battery 12 while the ringing contacts 10 10 of the various keys are all connected to the opposite pole of the ringing battery 12. When any one of the keys of a certain line is depressed to ringing position, it closes the circuit of ringing battery 12 through the ringer 11 of the said line, as will be hereinafter traced, and thereby rings the ringer to signal the party at that station to the telephone.

Each of the trunk lines of the system is divided into two parts, a part *a* (or *b*) common to all of the local stations of the intercommunicating system, and a part *A* (or *B*) extending to the magneto exchange. The two parts of each trunk line are inductively connected for talking purposes by a repeating coil 34 35 and condensers 17 and 18 connected in circuit with the respective sides of the repeating coil 34 35, so as to keep the magneto end of the trunk line separate from the common battery end of the trunk line. Each of the local lines *c*, *d* and *e* of the system, and each of the local portions *a* and *b* of the trunk lines, are supplied with talking current from talking battery 14 over a pair of impedance coils 15 36 connected to the respective sides of each of the metallic lines. The condensers 18 18 are for the purpose of keeping the circuits of battery 14 normally open across the corresponding trunk lines. The condensers 17 17 are for the purpose of allowing conversation to be carried on through the corresponding repeating coils 34 35, 34 35, but at the same time preventing ringing current sent from the magneto exchange, from flowing through the windings 34 34 of the corresponding repeating coils enough to shunt the corresponding ringers 16 16 and thereby render same unresponsive to the ringing current, each condenser 17 being of small capacity, preferably of one-half of a microfarad, for the purposes stated. The condensers 17 17 and 18 18 are connected in the middle of the corresponding windings 34

34 and 35 35, so as to properly balance the trunk lines. The ringers 16 16 are bridged across the corresponding trunk lines *A* and *B* to be rung from the magneto exchange to signal the attendant of the intercommunicating system to answer the incoming trunk calls. Each of the trunk lines *A* and *B* is provided with a kick-coil for throwing the corresponding drop at the magneto exchange, to signal the exchange operator to answer an intercommunicating outgoing trunk call. One winding 42 of each of the kick-coils is bridged across the corresponding trunk line *A* (or *B*), the other winding 43 of each kick-coil being connected from the pole of battery 12 to which ringers 11 11 are connected, to one limb of the local portion of the corresponding trunk line *a* (or *b*). The depression of any one of the keys on a trunk line, to ringing position, closes the circuit of battery 12 through the winding 43 of the corresponding kick-coil and thereby produces an impulse of current in the winding 43 which induces an impulse of current in the corresponding winding 42 and the magneto end of the trunk line *A* (or *B*), and thereby throws the corresponding trunk-line drop at the magneto exchange.

To show how one party on the system calls another party on the system and how connection is made for conversation between these two parties, I will assume that the party at station 1 calls the party at station 3, and will trace the operations and connections necessary to enable the party at station 1 to converse with the party at station 3. It will be understood that any party on the intercommunicating system may call and converse with another party on the system, in a manner similar to that next hereinbelow described, even if other stations on the system are busy; the ringing circuits having one individual conductor, and a common-return, for each ringer, and the talking circuits being metallic throughout. In calling the party at station 3, the party at station 1 first depresses his push-button key 3 to the ringing position, that is, until contact 7 thereof engages contact 10, and thereby closes a circuit from ringing battery 12 through conductor 21, contacts 10 7 of key 3 at station 1, limb 22 of line *e*, contacts 41 40 at the switch-hook of station 3, ringer 11 of station 3, and conductor 23 back to battery 12. The current from battery 12 now flowing through this circuit rings the ringer 11 at station 3. When the party at station 1 has thus rung station 3 sufficiently he releases his key 3 which returns to locking position, that is, to the position in which spring members 4 and 5 engage contacts 6 and 7, respectively, contacts 10 7 being now open, and then removes his receiver 20 from the switch-hook 25 which bridges his transmitter 19 and receiver 20, through conductors 29 and 30 of station 1, 130

and through contacts 4 6 and 5 7 of key 3 at station 1, across the limbs 28 and 22 of line *e*. Conductors 29 and 30 extend to all of the spring members 4 and 5, respectively, of the several push-button keys or switches at this station. The party at station 3 answers his call by lifting his receiver 20 from the switch-hook 25 which disconnects contacts 40 and 41 and connects contacts 26 and 27, and then 10 depresses his home key *H* to locking position which bridges his transmitter 19 and receiver 20 across the limbs 22 and 28 of his metallic line *e*. Now the talking circuit is closed from transmitter 19 at station 1, 15 through conductor 29 at station 1, contacts 4 6 of key 3 at station 1, limb 28 of line *e*, contacts 6 4 of key *H* at station 3, transmitter 19, receiver 20 and contacts 26 27, at station 3, contacts 5 7 of key *H* at station 3, limb 22 20 of line *e*, contacts 7 5 of key 3 at station 1, conductor 30, and contacts 27 26 and receiver 20, at station 1, back to transmitter 19 at station 1. This talking circuit is fed with current from talking battery 14 through impedance coils 15 and 36 of line *e*. The impedance coil 31 at each of the stations is of high impedance and of low resistance compared with the resistance of receiver 20, and is provided as a shunt around receiver 20 so 25 as to take most of the direct-current supply flowing through the transmitter 19 and at the same time allow receiver 20 to take approximately all of the talking currents passing through the transmitter 19. The direct 30 current which supplies the transmitter 19 is thus shunted from the receiver 20 so that the latter will not become demagnetized or overmagnetized thereby. When the conversation 35 between parties 1 and 3 is completed 40 these parties hang up their receivers on their respective switch-hooks, which opens the circuits of their talking sets at the respective switch-hooks and thereby stops the flow of current from battery 14 over the aforetraced talking circuit between stations 1 and 3. Party 1 leaves his key 3 depressed until he 45 desires to use his line again, either in communication with station 3 or with any of the other stations or trunk lines of the system. The depression of any of the other keys at 50 station 1, when it is desired to again use the talking set at station 1, releases the key 3 as hereinbefore stated. Party 3 also leaves his home key *H* depressed until he desires to use 55 his talking set again, his key *H* being restored by the depression of any of his other keys, as just stated in connection with station 1.

If any of the parties of the intercommunicating system desires to make an outgoing trunk call over a trunk line, as, for example, the party at station 2 calling out over trunk line *a* *A*, he first depresses his trunk key *T* (or *T*₂) corresponding to the trunk line, to 60 locking position, which closes the circuit of

ringing battery 12 through conductor 23, winding 43 of the kick-coil associated with the trunk line being used, limb 33 of the trunk line, contacts 7 10 of the trunk key which is being depressed, and conductor 21, 70 back to battery 12. The rush of current from battery 12 through this circuit causes winding 43 of the kick-coil to induce an impulse of current in the winding 42 of the kick-coil, which latter impulse of current traverses 75 the trunk line *A* leading to the magneto exchange and throws the corresponding trunk-line drop at the magneto exchange. Now the calling party at station 2 releases his trunk key which returns to locking position 80 so that contacts 4 and 5 thereof engage contacts 6 and 7, respectively, and then removes his telephone receiver 20 from the switch-hook 25 which connects contacts 26 and 27 and thereby bridges his transmitter 19 and 85 receiver 20 through conductors 29 and 30 of his station, and contacts 4 6 and 5 7 of his depressed trunk key, across the limbs 32 33 of the trunk line *a* for conversation with the magneto exchange. The conversation may 90 now be carried on with the party connected through the magneto exchange, over the trunk line *a* *A*, through the repeating coil 34 35 associated with the trunk line. The transmitter 19 at station 2 is supplied with talking 95 current from battery 14 through impedance coils 15 and 36 of the trunk line to which station 2 is connected, limbs 32 and 33 of the trunk line, contacts 6 4 and 7 5 of the depressed trunk key, conductors 29 and 30 of 100 station 2, and contacts 27 26 and impedance coil 31 of station 2. When the conversation is completed the party at station 2 hangs up 105 his receiver 20 on the switch-hook 25 and thereby breaks the circuit of battery 14 through his telephone. The party at station 2 may now depress the depressed trunk key from locking position to ringing position and thereby cause the kick-coil 42 43 to throw the disconnect drop at the magneto exchange, as hereinbefore described in connection with the line drop at the magneto exchange. The party at station 2 leaves his trunk key depressed until he desires to use 110 his talking set again, his trunk key being restored to normal position by the depression of any of his other keys, as stated above in connection with stations 1 and 3.

When the operator at the magneto exchange desires a connection with a station of 120 the intercommunicating system, she sends a ringing current over a trunk line *A* (or *B*) and thereby rings the ringer 16 associated with the trunk line, in the usual manner. The attendant at station 1 answers the incoming trunk call by depressing his corresponding trunk key *T* (or *T*₂) to locking position, and then removes his receiver 20 from the switch-hook 25 which bridges his transmitter 19 and receiver 20 through conductors 125 130

29 and 30 of station 1 and contacts 4 6 and 5 7 of the depressed trunk key at station 1, across the limbs 32 33 of the trunk line *a* (or *b*). Now the attendant converses with the 5 party connected from the magneto exchange over the trunk line and learns from him the station of the intercommunicating system with which communication is desired. Assuming this latter station to be station 2 of 10 the intercommunicating system, the attendant calls station 2 by depressing his key 2, at station 1, to ringing position which signals the party at station 2 by closing the circuit of ringing battery 12 through conductor 21, 15 contact 10 7 of key 2 at station 1, limb 22 of line *d*, contacts 41 40 of station 2, ringer 11 of station 2, and conductor 23 back to battery 12. Current flowing through this circuit rings the ringer 11 of station 2 which signals 20 the party at this station. When the attendant depresses his key 2 to signal the party at station 2 he automatically releases his depressed trunk key *T* (or *T*₂) and restores same to normal position in which position all 25 of the contacts of the key are open. Key 2 of station 1, being now released and moving to locking position, bridges the telephone transmitter 19 and receiver 20 of station 1 across the limbs 28 22 of line *d*, as hereinbefore described. When the party at station 2 answers the signal of his ringer 11, he depresses his home key *H* to locking position and removes his receiver 20 from the switch-hook 25 which bridges his transmitter 19 and 35 receiver 20 across the limbs 28 22 of his line *d*, as hereinbefore described. The attendant now converses with the party at station 2 and instructs him to make connection with the calling trunk line *a* (or *b*) to answer the 40 incoming trunk call. The transmitters 19 19 of stations 1 and 2 are now supplied with talking current from battery 14 through impedance coils 15 and 36 of line *d*, in a manner similar to that hereinbefore described. The 45 attendant now hangs his receiver 20 upon the switch-hook 25 which breaks his transmitter bridge across the limbs of line *d* as will be readily understood. Now the party at station 2 depresses his trunk key *T* (or *T*₂) corresponding to the calling trunk line, which releases his home key *H* and thereby bridges his transmitter 19 and receiver 20 through 50 conductors 29 and 30 of station 2, and contacts 4 6 and 5 7 of the depressed trunk key 55 at station 2, across the limbs 32 33 of the calling trunk line. Now the party at station 2 may converse with the party who is connected through the magneto central exchange and the trunk line *A a* (or *B b*), 60 through the medium of repeating coil 34 35 of the corresponding trunk line; transmitter 19 of station 2 being supplied with talking current from battery 14 through impedance coils 15 and 36 of the calling trunk line, as 65 hereinbefore described. When the conver-

sation is completed and the party at station 2 hangs his receiver 20 on the switch-hook 25 he breaks the bridge of his talking set across the trunk line with which his talking set is connected, and thereby stops the flow of current from battery 14 through his transmitter 19. The party at station 2 may give a disconnect signal to the magneto exchange by depressing his depressed trunk key to ringing position which sends an impulse of current 70 from battery 12 through winding 43 of the corresponding kick-coil, and thus induce an impulse of current through the winding 42 of the said kick-coil which current traverses the corresponding trunk line *A* (or *B*) and 75 throws the disconnect drop at the magneto exchange, as hereinbefore described. The party at station 2 leaves his trunk key depressed to locking position until he desires to use his talking set again when the depression 80 of any of the other keys at his station releases the depressed trunk key. 85

It will be readily seen that the ringing and talking keys of this system are self-indicating, that is, they indicate the party with whom conversation was last had, or, in the case of calling a party who does not respond, they indicate the station with which communication is desired, so that the calling party may again readily depress the proper key to 90 ringing position to signal the called party a 95 second time.

I do not wish to limit this invention to all of the particular details herein shown, as many modifications of same may be made 100 without departing from the scope of the appended claims.

What I claim as my invention is:

1. An intercommunicating telephone system having a plurality of local lines common 105 to a plurality of stations, a trunk line extending from the intercommunicating system to a magnetic exchange, a repeating coil inductively connecting one of the said local lines with the trunk line whereby conversation 110 may be carried on from the various said stations over the trunk line, a kick-coil having one winding bridged across the trunk line at the intercommunicating system, and means at the various said stations for causing the 115 kick-coil to throw a drop on the trunk line at the magneto exchange.

2. An intercommunicating telephone system having a plurality of local common-battery lines common to a plurality of stations, 120 a trunk line extending from the intercommunicating system to a magneto exchange, a repeating coil inductively connecting one of the local lines with the trunk line for talking purposes whereby the common-battery local line is kept separate from the magneto trunk line, a kick-coil having its primary winding connected with the intercommunicating system and its secondary winding bridged across the trunk line, and means for sending an im- 125 130

pulse of current through the primary of the kick-coil to induce an impulse of current in the secondary of the kick-coil and the trunk line, to throw a drop connected with the 5 trunk line at the magneto exchange.

3. An intercommunicating telephone system having a plurality of local lines common to a plurality of stations, a trunk line extending from the intercommunicating system to a 10 magneto exchange, a repeating coil inductively connecting one of the local lines with the trunk line for talking purposes, a kick-coil associated with the trunk line at the intercommunicating system for throwing a 15 drop connected with the trunk line at the magneto exchange, and a condenser in series with the trunk-line side of the repeating coil whereby any considerable portion of the impulse of current produced in the trunk line 20 by the kick-coil is kept from flowing through the repeating coil.

4. An intercommunicating telephone system having a plurality of local lines common to a plurality of stations, a trunk line extending 25 tending to a magneto exchange, a repeating coil inductively connecting one of the local lines with the trunk line for talking purposes, a pair of condensers in series with the respective windings of the repeating coil, a 30 kick-coil at the intercommunicating system having its secondary bridged across the trunk line, and means for causing the kick-coil to send an impulse of current over the trunk line to throw a drop at the magneto 35 exchange.

5. An intercommunicating telephone system having a plurality of local lines common to a plurality of stations, a trunk line extending from the intercommunicating system to a 40 magneto exchange, a kick-coil having its secondary bridged across the trunk line at the intercommunicating system, a suitable source of current at the intercommunicating system, and suitable ringing keys at the respective 45 stations of the intercommunicating system whereby a party at any of the said stations may send an impulse of current through the kick-coil to cause the latter to throw a drop associated with the trunk line at the 50 magneto exchange.

6. An intercommunicating telephone system having a plurality of local lines common to a plurality of stations, a source of talking current for the local lines, impedances feed- 55 ing talking current from the said source to the various local lines, a trunk line extending from the intercommunicating system to a magneto exchange, a repeating coil inductively connecting one of the local lines with 60 the trunk line for talking purposes, a pair of condensers connected in series with the respective windings of the repeating coil, a kick-coil at the intercommunicating system having its secondary winding bridged across the 65 trunk line, ringing and talking keys at each

of the stations of the intercommunicating system, a source of ringing current associated with the intercommunicating system, and means whereby a party at any of the said stations may send an impulse of ringing 70 current through the kick-coil to cause the latter to throw a drop connected with the trunk line at the magneto exchange.

7. An intercommunicating telephone system having a plurality of local lines common to a plurality of stations, a trunk line extending from the intercommunicating system to a magneto exchange, a ringer bridged across the trunk line at the intercommunicating system whereby the operator at the magneto 75 exchange may signal a party at the intercommunicating system, a repeating coil inductively connecting one of the said local lines with the trunk line for talking purposes, and a condenser connected in series with the 80 trunk-line side of the repeating coil whereby any considerable portion of the ringing current sent from the magneto exchange to ring the said ringer is prevented from flowing through the repeating coil. 85

8. An intercommunicating telephone system having a local line common to a plurality of stations, a trunk line extending from the intercommunicating system to a magneto exchange, a repeating coil inductively 90 connecting the said local line with the trunk line for talking purposes, a condenser in circuit with the trunk-line side of the repeating coil to permit talking currents to pass through the repeating coil, but being of 95 small enough capacity to prevent any considerable amount of signaling current from passing through the repeating coil, a ringer bridged across the trunk line at the intercommunicating system for receiving incoming 100 trunk calls, and a kick-coil at the intercommunicating system, the secondary of which is bridged across the trunk line whereby a party at the intercommunicating system may cause an impulse of current to be 105 sent over the trunk line to throw a drop connected with the trunk line at the magneto exchange. 110

9. In a telephone system, a trunk line and a local line inductively connected for conversation by a repeating coil, a condenser of small capacity in series with a winding of the repeating coil whereby any considerable quantity of signaling current is prevented from passing through the repeating coil, a 115 kick-coil associated with the trunk line at the local line whereby an impulse of current may be sent over the trunk line for signaling from the local line to an exchange, and a ringer associated with the trunk line at the 120 local line for receiving signals sent to the local line over the trunk line. 125

10. An intercommunicating telephone system having a plurality of local lines common to a plurality of stations, one of which sta- 130

tions is designated an attendant's station, a trunk line extending from the intercommunicating system to a magneto exchange, a repeating coil inductively connecting one of the local lines with the trunk line for talking purposes, a ringer bridged across the trunk line at the attendant's station for receiving incoming trunk calls, switching mechanism at the attendant's station whereby the attendant may connect his telephone set with the last mentioned local line for conversation over the trunk line, switching mechanism at the attendant's station whereby the attendant may signal any of the other stations of the intercommunicating system to answer an incoming trunk call, and suitable mechanism at the various stations of the intercommunicating system whereby a party at any of the stations thereof may connect his telephone set with the last mentioned local line for conversation over the trunk line.

11. In a telephone system, a trunk line, a local line extending to a plurality of stations of an intercommunicating system, a repeating coil inductively connecting the trunk line with the local line for conversation, a kick-coil associated with the trunk line at the local line, means at each of the said stations controlling the kick-coil whereby an impulse of current may be sent over the trunk line from any of the said stations, for signaling from the local line to an exchange, and a signaling device associated with the trunk line at the local line for receiving signals sent to the local line over the trunk line.

12. In a telephone system, a trunk line, a local line extending to a plurality of stations of an intercommunicating system, a repeating coil inductively connecting the trunk line with the local line for conversation, a condenser of small capacity in series with a winding of the repeating coil whereby any considerable quantity of signaling current is pre-

vented from passing through the repeating coil, and a signaling device bridged across the trunk line at the local line for receiving signals sent to the local line over the trunk line.

13. In a telephone system, a trunk line, a local line extending to a plurality of stations of an intercommunicating system, a repeating coil inductively connecting the trunk line with the local line for conversation, a condenser of small capacity in series with a winding of the repeating coil whereby any considerable quantity of signaling current is prevented from passing through the repeating coil, a kick-coil associated with the trunk line at the local line, and means at each of the said stations controlling the kick-coil whereby an impulse of current may be sent over the trunk line from any of the said stations, for signaling from the local line to an exchange.

14. An interior telephone system including a plurality of stations, a trunk line leading to an exchange, a switching key at an interior station being adapted to have at least two operating positions, in one of which it is adapted to connect an interior system with said trunk line, a signal device at the exchange end of the trunk line adapted to respond to impulses of current, a primary kick coil circuit which is closed by said switching key when occupying a different operating position, and a secondary kick coil circuit in inductive relation with said primary kick coil circuit and including the signal device at the exchange end of said trunk line.

As inventor of the foregoing I hereunto subscribe my name, in the presence of two subscribing witnesses, this 6th day of May, 1908.

ELMER R. CORWIN.
